BALANCED TRANSMISSION LINE
OSCILLATOR

Eric Osborne Willoughby, London, England, assignor to International Standard Electric Corporation, New York, N. Y.

Application February 27, 1942, Serial No. 432,601
In Great Britain February 28, 1941

2 Claims. (Cl. 250—36)

1

The present invention relates to short wave and ultra-short wave oscillators and particularly unbalanced oscillators, i. e. oscillators using a single valve or two or more valves in parallel, and according thereto, a trimming condenser tied to the plate line is provided to balance the grid and plate transmission lines to cathode.

The invention will be better understood from the following description taken in conjunction with the accompanying drawings which illustrate ultra-short wave oscillators. It will be understood, however, that the invention is equally applicable to short wave oscillators with larger valves.

In the drawings,

Figs. 1a, 1b and 1c illustrate known types of ultra-short wave oscillators utilising lengths of transmission line together with the interelectrode capacity of a thermionic valve as the tank circuit elements. The earth is normally the screening case of the oscillator.

Figure 2 shows schematically a tank circuit for an ultra-short wave oscillator embodying the invention, and

Figure 3 shows a slightly modified arrangement.

In Fig. 1a, the oscillator valve or tube T includes a cathode C, grid G, and an anode A. One-quarter wavelength transmission line conductors GL and AL are connected, respectively, with the grid and anode of valve T at the right hand end of line AL, GL, the left hand end of the line being effectively short circuited through the condenser plates E. The line AL, GL in combination with the inherent capacity C_{gc} between the grid G and cathode C and with the inherent capacity C_{pc} between the anode A and cathode C, serves as a tank circuit. A positive high tension voltage source HT is connected through the radio frequency choke coil RFC with the left end of line AL for supplying anode current to the valve T. A connection is provided from ground through grid leak resistance M with the left end of line GL for the grid G. A line CL of adjustable length, connects from ground with the cathode C. The screening can, or shield K, provides an "earth" or ground connection for the circuits of the oscillator.

In Fig. 1b, valve T is connected at the right hand end of line AL, GL, the left end of the line being open, and the connections for coil RFC and leak M being made at the center of the line.

In Fig. 1c, the valve T is connected at the center of line AL, GL, the connections for coil RFC and leak M being made near the right end of the line.

2

Referring to Figs. 1a, 1b and 1c, in such circuits as illustrated the grid cathode capacity C_{gc} is inherently larger than the plate cathode capacity C_{pc}, and there is an unbalanced current to earth through the cathode return lead CL which is commonly tuned to the oscillation by varying the length of transmission line attached to the filament cathode terminals of the valve and returned to the screening can or shield K of the oscillator.

It now appears that such tuning of the cathode line can have no appreciable effect on balancing the oscillator tank circuit, and in carrying out this invention a low impedance is provided in

15 the cathode to earth path (such for instance as may often be obtained by directly short circuiting the cathode to oscillator screening can K) and the circuit is tuned by means of a small trimming condenser between plate lead and earth or screen can, thereby providing a parallel reactance between plate and screen can or earth which reactance can be made to balance the plate and grid transmission lines of the oscillator tank circuit about "earth" or the screening can.

20 Referring to Figure 2, the tank circuit may be modified to any of the transmission line arrangements known to the art and typified by Figures 1a, 1b and 1c.

The anode of the valve is indicated at A, control grid at G, and the cathode (indirectly heated over the circuit from the low voltage source LT to ground) at C. Anode and grid leads are shown respectively at AL and GL as lengths of concentric transmission line and the cathode lead as CL, its inductance being represented by L. Output from the valve is obtained by means of a coaxial line LO. The small trimming condenser between the plate lead AL and earth or screen can is indicated at Cb. This condenser may be connected between the plate lead AL and cathode directly if it is practically more convenient. The outer conductors of the plate and grid transmission lines are earthed for high frequency currents through plates E forming condensers with the screening can K', a sheet of mica N being inserted if desired between E and K'.

This balancing adjustment of condenser Cb gives strongest oscillation and maximum output, and in practice the balancing point is shown most markedly by the grid current which reaches a maximum value corresponding to maximum plate and grid voltage swings, the grid leak being increased, if necessary, to maintain the grid dissipation at a reasonable value.

55 It is well to note that the essential adjustment is an increase of plate-cathode capacity by an

amount corresponding to $C_{gc} - C_{pc}$, the adjustment being affected by the inductance of the leads to the electrodes inside the valve, and in practice the adjustment amounts to a balance of plate-to-cathode and grid-to-cathode reactances of the valve and tank circuit in the oscillator.

Since the grid line GL is already damped by the grid leak M and since the trimming condenser C_b adjusts reactance of the plate line AL for an unbalanced output, it is advisable to tap the output lead LO directly on the plate line, for if the transmission line is correctly matched at the load end, due to the high ratio of volt-amperes to watts in the short wave circuits, the reactance adjustment of the trimming condenser C_b will necessarily be small.

It should be noted that although push-pull arrangements of valves are convenient for oscillators, they result in relatively high capacity across the transmission lines and limit the frequency that can be obtained, while use of inverted valves, that is, of the grounded grid type, in push-pull although reducing this capacity effect inherently reduces the ratio of alternating anode voltage to direct current anode voltage and their effective efficiency, hence the above balancing circuit for single valve oscillation often is the most satisfactory solution of the problem of obtaining a desired output with a given value at a relatively high frequency.

Theory

Referring to Fig. 2, the unbalance current through AL to earth is:

$$\frac{V}{j(X_L - X_{C_{pc}})} - \frac{V}{j(X_L - X_{C_{gc}})} = \frac{V}{j[(X_L - X_{C_{pc}})(X_L - X_{C_{gc}})]} \left[\frac{X_{C_{pc}} - X_{C_{gc}}}{(X_L - X_{C_{pc}})(X_L - X_{C_{gc}})} \right]$$

where V is the voltage of the line AL, GL above ground, j is $\sqrt{-1}$, X_L is the reactance of inductance L, $X_{C_{pc}}$ is the reactance of capacity C_{pc} , and $X_{C_{gc}}$ is the reactance of capacity C_{gc} . This current must be equal to the current through the balancing circuit

$$= \frac{V}{j(X_{Lb} - X_{Cb})}$$

where X_{Lb} and X_{Cb} are the reactances of the balancing inductance and the balancing capacity, respectively.

Hence for a balance:

$$(X_{C_{pc}} - X_{C_{gc}})(X_{Lb} - X_{Cb}) = (X_L - X_{C_{pc}})(X_L - X_{C_{gc}})$$

Since C_{gc} is inherently greater than C_{pc} from the construction of the valve, the balancing method must be resorted to, to balance the transmission line tank circuits to earth. It is important to notice, however, that since L the inductance of the cathode lead carries the unbalance current, so long as its reactance is reasonably small such as often can be obtained merely by shorting the cathode to the screening case of the oscillator, it will have little effect on the amplitude of the grid voltage and the only tuning necessary becomes the balancing adjustment provided the transmission lines are correct to length, otherwise a small trimming condenser will be required across the lines for tuning the valve.

The balancing and trimming condensers may be combined as two series condensers in an arrangement as indicated in Fig. 3 in which C_1 and C_2 are two condensers in series across the plate

and grid lines and with the common plate earthed, the capacity C_b , shown as a separate element in Fig. 2, being included as a part of the capacity C_1 in Fig. 3. With C_1 greater than C_2 , the difference $C_1 - C_2$ is equal to the balancing capacity C_b of Fig. 2 and the series value of C_1 , C_2 namely,

$$\frac{C_1 C_2}{C_1 + C_2}$$

is the trimming or tuning adjustment.

Magnification factor (μ) of valves

The type of oscillator shown in Figs. 1a, 1b and 1c is eminently suitable for low " μ " tubes, and the grid voltage swing obtained by the arrangement according to this invention is higher than is desirable for a good output with high values of " μ ," the resistance of the grid leak having to be increased to an extent that makes the operating angle of the valve very small.

In this case a capacitative reactance placed in the cathode and filament leads (i. e. in series with the inductance L) is necessary to reduce the drive to the grids to a satisfactory value, the unbalance current to ground due to C_{gc} being larger than C_{pc} will then result in the grid-cathode voltage swing being reduced and the drive brought to a satisfactory value without too high a value of grid leak, resulting in too small an operating angle. A length of transmission line or a small condenser in the cathode lead will then be satisfactory. This, however, does not do away with the need of balancing and the balancing condenser C_b is still necessary.

35 What is claimed is:

1. An oscillator for short and ultra-short waves including a valve having grid and plate electrodes and a cathode, a grounding impedance for said cathode, said impedance having some inductive reactance inherent therein at the frequencies involved, the grid-cathode internal capacity of the valve being greater than the plate-cathode internal capacity, transmission line circuits coupled to said electrodes, and a trimming condenser, having a capacity corresponding to the difference between said capacities, connected externally of the valve between the plate line and ground, arranged to balance said transmission lines with respect to the cathode, and to tune the out-of-balance current to ground through said inherent cathode grounding impedance.

2. The oscillator of claim 1 wherein the transmission line circuits coupled to said electrodes comprise anode and grid leads terminating in grounded condensers and wherein the output of said oscillator is taken at a point on the anode lead in advance of said grounded condensers.
